CLAIM

The ornamental design for a metal roof panel of indeterminate length, as shown and described.

DESCRIPTION

FIG. 1 is a top, front and left side perspective view of a metal roof panel of indeterminate length showing my new design; FIG. 2 is a bottom, front and right side perspective view thereof;

FIG. 3 is a front elevational view thereof;

FIG. 4 is a rear elevational view thereof;

FIG. 5 is a left side elevational view thereof, the right side elevational view being a mirror image;

FIG. 6 is a top plan view thereof; and,

FIG. 7 is a bottom plan view thereof.
